UNITED STATES PATENT OFFICE.

WILLARD E. CLEVELAND, OF OREGON, ILLINOIS, ASSIGNOR TO NATIONAL PIANO PLAYER COMPANY, OF OREGON, ILLINOIS, A CORPORATION OF ILLINOIS.

NOTE-SHEET-FEED MECHANISM FOR MUSICAL INSTRUMENTS.

No. 888,587.

Specification of Letters Patent.

Patented May 26, 1908.

Application filed August 26, 1907. Serial No. 390,157.

To all whom it may concern:

Be it known that I, WILLARD E. CLEVELAND, a citizen of the United States, residing at Oregon, in the county of Ogle and State of Illinois, have invented certain new and useful Improvements in Note-Sheet-Fee Mechanism for Musical Instruments, of which the following is a specification.

The object of this invention is to automatically start the movement of the note sheet immediately after the pump has been started.

This invention consists in the employment of a pneumatic and a weighted frame which is released when the air is exhausted from the pneumatic, thereby acting upon a pressure roller to move it against the note sheet laid in contact with the rotating feed roller with sufficient pressure to insure the movement of the note sheet.

In the accompanying drawings. Figure 1 is an elevation of my improvements. Fig. 2 is a vertical transverse section on dotted line *a a* Fig. 1, in which the parts are in the position they occupy when at rest. Fig. 3 is a similar section in which the parts are in operative position.

The side plates 1 and 2 are held separated by a suitable number of cross-rods 3. A note sheet feed roller 4 is supported by the side plates in a manner to permit of its rotation, and is intended to be constantly rotated during the operation of the instrument by any suitable mechanism, which is not deemed necessary to be shown. Rollers 5, 6, 7 and 8 are supported by the side plates in a manner to be rotated by the movement of the note sheet and serve to direct the note sheet from one roll to the other. A tracker-bar 9 is located between the rollers 6 and 5 and is supported by the side plates. A note sheet 10 is supported by the rollers 4, 5, 6, 7 and 8 and passes over the tracker-bar 9 as shown in the cross-sections. A pressure roller 11 is supported by the side plates in a manner to rotate idly, and capable of a bodily movement toward and from the feed roller 4 by its journals being located in the slots 12 in the side plates.

A frame is composed of two end bars 13 pivoted to the inner face of the side plates by the screws 14, and adjacent the point of pivot they are enlarged to form cams 15. A roller 16 is pivotally supported by the end-bar 13.

A brace 17 connects the end-bars 13. To 55 one of the side plates is fixedly connected a pneumatic 18 and the tube 19 is intended to be connected with the exhaust chamber of the instrument with which an exhaust air-pump has a connection, such chamber being 60 old I have not deemed it necessary to show it. A pin 20 is guided in an ear 21 extending from one of the side plates in a manner to slide lengthwise freely therewith. A link 22 forms a connection between the pin 20 and 65 pneumatic.

When the instrument is not playing, the swinging frame is held upright by the pin 20 protruding sufficiently to receive one of the end-bars 13 of the frame as shown at Fig. 2. 70 To the inner face of each of the side plates is pivoted a bar 23 about midway of its length. The lower portions of these bars are adapted to engage the journals of the pressure roller 11, and their upper portions are adapted to 75 be engaged by the cams 15 of the end bars 13.

The operation of my improvements are as follows. When the instrument is at rest, for instance, when a new note sheet has to be placed in position in connection with the 80 various rollers, the swinging frame will be held in its elevated position by the pin 20 as shown at Fig. 2, and the pressure roller 11 may stand free of the feed roller 4. After the note sheet has been properly placed in 85 connection with the various rollers, the feed roller is set in rotative motion by any suitable means. The action of the pump will be to exhaust air from the pneumatic, thereby collapsing it, and this collapsible action of 90 the pneumatic will retract the pin 20 which will allow the swinging frame to fall. This frame in falling will cause the cams 15 to act upon the upper portions of the bars 23 and move the lower portions of the bars against 95 the journals of the pressure roller 11 and move the roller bodily against the feed roller 4, as shown at Fig. 3. The weighted roller 16 will rest against the note sheet and cause the sheet to embrace a greater surface of the 100 feed roller thereby increasing the driving power of the feed roller upon the note sheet. When it is desired to place a new note sheet in the instrument, the swinging frame is manually raised behind the pin 20 which 105 movement, will permit the pressure roller to be separated from the feed roller thereby leaving the note sheet free.

I claim as my invention.

1. In a device of the character described, the combination of a feed roller, a pressure roller normally out of contact therewith, 5 mechanically operated means for holding the pressure roller in contact with the feed roller at times, means for holding the mechanical means inoperative and pneumatic devices for releasing the holding means.
- 10 2. In a device of the character described, the combination of a feed roller, a pressure roller normally out of contact therewith, a swinging frame adapted to hold the pressure roller in contact with the feed roller at times, 15 means for holding the swinging frame inoperative, and pneumatic devices for releasing the holding means.
- 20 3. In a device of the character described, the combination of a feed roller, a pressure roller normally out of contact therewith, a swinging frame having ends formed in cams, pivoted bars located between the cams and the journals of the pressure roller, means for holding the frame inoperative, and pneumatic devices for releasing the holding means.
- 25 4. In a device of the character described, the combination of a note sheet, a feed roller

over which the note sheet travels, an idle roller adapted to engage the note sheet and increase the surface contact of the note sheet 30 with the feed roller, means holding the idle roller inoperative and pneumatic devices for releasing the holding means.

5. In a device of the character described, the combination of a note sheet, a feed roller 35 over which the note sheet travels, a swinging frame comprising an idle roller adapted to engage the note sheet and increase the surface contact of the note sheet with the feed roller, means for holding the frame and 40 consequently the idle roller inactive, a pressure roller normally out of contact with the feed roller, means operated by the swinging frame for holding the pressure roller in contact with the feed roller at times, and pneumatic devices for releasing the first named 45 holding means.

In testimony whereof I have hereunto set my hand in presence of two subscribing witnesses.

WILLARD E. CLEVELAND.
